UNITED STATES PATENT OFFICE.

JOHN SCHEER, OF ATLANTA, GEORGIA, AND GEORGE F. SCHEER, OF RICHMOND,
VIRGINIA.

ENGRAVER'S BLOCK.

1,204,696.

Specification of Letters Patent. Patented Nov. 14, 1916.

Application filed March 29, 1916. Serial No. 87,560.

To all whom it may concern:

Be it known that we, JOHN SCHEER and GEORGE F. SCHEER, citizens of the United States, residing at Atlanta, in the county of Fulton and State of Georgia, and Richmond, in the county of Henrico and State of Virginia, respectively, have invented certain new and useful Improvements in Engravers' Blocks, of which the following is

10 a specification.

The invention relates to an engraver's block, and more particularly to the class of jaw attachments for engravers' blocks.

15 The primary object of the invention is the provision of an attachment of this character, wherein the separable pins for insertion in the jaws of the engraver's block, are entirely dispensed with, thereby eliminating the possibility of the loss of said pins, and also the 20 labor and time required in inserting and interchanging the same in the jaws of the block, for the clamping of the work to be engraved.

25 Another object of the invention is the provision of an attachment of this character, wherein the series of clamping pins are resiliently mounted therein, and are supported upon a movable plate or follower, so that one or more of said pins can be displaced 30 while other pins are engaged with the work, thereby enabling the execution of the engraving with perfect freedom and successfully, as well as the use of the jaws without interference by the pins.

35 A further object of the invention is the provision of an attachment of this character, wherein the construction thereof is novel in form, and the pins readily and easily adjusted with despatch, for the successful 40 clamping of the work to be engraved.

A still further object of the invention is the provision of an attachment of this character, which is extremely simple in construction, thoroughly reliable and efficient 45 in operation, strong, durable, and inexpensive in manufacture.

With these and other objects in view the invention consists in the features of construction, combination and arrangement of 50 parts as will be hereinafter fully described, illustrated in the accompanying drawing, and pointed out in the claims hereunto appended.

In the accompanying drawing, Figure 1, 55 is a side elevation of an engraving block

showing the attachment constructed in accordance with the invention applied. Fig. 2, is a top plan view. Fig. 3, is a vertical sectional elevation. Fig. 4, is a sectional view on the line 4—4 of Fig. 1. Fig. 5 is a 60 fragmentary view showing in detail a piece of work clamped by the device.

Similar reference characters indicate corresponding parts throughout the several views in the drawing.

Referring to the drawing in detail, A, designates the ball base, B, the pedestal, which is detachable therefrom, C, the head upon the pedestal, and D, the adjustable jaws supported in the head, which constitute 70 the engraver's block, of the ordinary well known construction, and having applied thereto the attachment hereinafter fully described.

The attachment comprises complementary 75 shells 5, each being made in two or more parts, suitably fastened together, to permit separation thereof in event access is to be had to the interior of the shell, and is of a shape corresponding to the jaw on the block, the upper end of the shell being formed with a closed top 6, while the opposite end is open for the telescoping of said shell upon its respective jaw D, of the block. The shell 5, is fastened to the jaw D, in any 80 suitable manner.

Interiorly of the shell 5, is a movable follower comprising spaced upper and lower plates 7 and 8, respectively, which are united to each other through the medium of rivets 9, the plate 7, being formed with a plurality of holes 10, arranged in rows spaced apart, through which work clamping pins 11, having lower terminal heads 12, which form stops for the same to limit the 90 sliding movements of the pins 11, in one direction in said plate 7, while formed on said pins are annular shoulders 13, against which bear coiled springs 14, surrounding said pins 11, and also bear against the plate 7, for resiliently supporting the pins, which are adapted to slide through holes 15, formed in the top 6, of the shell, for clamping engagement with a piece of work to be 95 engraved.

Jounaled in opposed walls of the shell 5, below the follower therein is a horizontal shaft 16, which carries a cam 17, adapted to act upon the follower for raising and lowering the same, whereby the pins 11, will 100 105 110

be projected through the holes 15, in the top 6, of said shell or for retracting said pins 11, interiorly of the latter.

Mounted upon the shaft 16, is a ratchet 5 wheel 18, with which engages a spring pawl 19, adapted to lock the said shaft 16, against rotation in one direction, while the same is free for rotation in the other direction, the pawl 19, being suitably mounted upon the 10 inner face of one wall of the shell. The shaft 16, has one end formed with screw threads 20, for the detachable engagement of a key 21, therewith, to permit the turning of said shaft for the adjustment of the 15 follower with the pins 11, therein. The threaded end 20 of the shaft 16 is extended exteriorly of the shell 5 for the engagement of a key 21 thereon as the occasion may require.

20 Each pin 11 near its outer end has formed therein a notch 22 serving as a seat for the work when clamped by the pin.

It will be noted that on turning the shaft the pins 11 can be raised to any desired 25 height by the cam 17 acting upon the fillers which carry the pins. When the pins 11 are protruded beyond the tops of the shells and the work is applied by placing the same over certain of the pins which depresses 30 those lying beneath the work, the latter will be brought into position to be gripped by the pins adjacent to the edge thereof, that is to say, the pins will lie next to the edges of the work when the shells are moved toward 35 each other, while the other remaining pins protruded may be depressed by the instrument or the tool worked with should occasion require, although in a number of instances the character of the work to be en- 40 graved has a face that can be operated upon without any interference by the pins which remain protruded beyond the top of the shell and not acting as clamps for the work. It will be apparent that any one or a num- 45 ber of the pins 11 can be depressed against the resistance of the springs 14 so as to per-

mit certain of said pins which remain pro- truded beyond the tops of the shells to en- gage and clamp a piece of work on oper- ating the jaws of the block.

50 What is claimed is:

1. An attachment for engravers' blocks having jaws movable toward and away from each other, shells mounted upon the jaws, a plurality of vertically yieldable pins 55 movably mounted in the shells to be pro- truded beyond the tops thereof, and means for vertically moving all of the pins in a single operation.

2. An attachment for engravers' blocks 60 having jaws movable toward and away from each other, shells mounted upon the jaws, a plurality of vertically yieldable pins movably mounted in the shells to be pro- truded beyond the tops thereof, cams for 65 action upon the supports for the pins to raise the same, and means for locking the cams against movement in one direction to sustain the supports in vertically adjusted position.

70 3. An attachment for engravers' blocks having jaws movable toward and away from each other, shells mounted upon the jaws, a plurality of vertically yieldable pins 75 movably mounted in the shells to be pro- truded beyond the tops thereof, cams for action upon the supports for the pins to raise the same, means for locking the cams against movement in one direction to sustain the supports in vertically adjusted po- 80 sition, and means for rotating the cams.

In testimony whereof we affix our signatures in presence of two witnesses.

JOHN SCHEER.
GEORGE F. SCHEER.
